Frank Beekman

UNITED STATES PATENT OFFICE.

EDWARD B. HESS, OF BROOKLYN, NEW YORK, ASSIGNOR TO ROYAL TYPEWRITER COMPANY, INC., OF NEW YORK, N. Y., A CORPORATION OF NEW YORK.

TYPE-BAR-TENSION-ADJUSTING MEANS.

1,241,214.

Specification of Letters Patent. Patented Sept. 25, 1917.

Application filed May 10, 1917. Serial No. 167,642.

To all whom it may concern:

Be it known that I, EDWARD B. HESS, a citizen of the United States, and a resident of the borough of Brooklyn, in the city of New York, county of Kings, and State of New York, have invented certain new and useful Improvements in Type-Bar-Tension-Adjusting Means, of which the following is a specification.

- 10 The present invention relates generally to typewriting machines and has more particularly reference to means for adjusting the tension under which the type-bars are held in their inactive position.
- 15 In the Hess and Myers Patent No. 1,212,947 there is disclosed a construction of typewriter in which the type-bars are connected to a universal bar by means of a suitable link. Surrounding each link is a tension 20 spring which is attached at one end to a member connected to the type-bar and at its other end to a frame pivotally supported in the casing of the machine. This frame has an adjustable plate at its upper free 25 end which receives the springs and has at its lower free end a bushing for the reception of an adjusting screw which latter abuts against the rear wall of the casing, so that, by turning the screw, the frame is swung on 30 its pivots and the tension of all the springs of the type-bars is adjusted. In view of the fact that these parts are located within the casing of the machine, they are not accessible from the exterior thereof, and, in 35 order to make the adjustment, it is necessary to reach up inside the casing from beneath the same. As is well known, typewriting machines are usually fastened to the table or desk on which they are supported, and, 40 in order to vary the tension of the springs of the type bars, it is necessary to remove the fastening means for the machine as a whole in order that proper access may be gained to the bars. Naturally, the removal 45 and replacement of the fastening means of the machine as a whole occupies an undue amount of time of the repair man and it is the object of this invention to obviate this difficulty and to enable the springs of all the 50 type-bars to be adjusted in unison without the necessity of removing the machine from its support.

The invention comprises essentially a construction whereby detachable means, extending through the rear wall of the casing, may be utilized for the purpose of adjust-

ing the frame, within the casing, on its pivotal supports.

In the accompanying drawings is shown a portion of a typewriting machine similar to the disclosure of Patent No. 1,212,947, but to avoid mere repetition of parts already known only the elements immediately adjacent to the adjusting frame are shown.

Figure 1 is a vertical sectional view 65 through the rear portion of a typewriting machine showing the end of the type-bar system and the connections therefrom to the universal bar and to the adjusting frame.

Fig. 2 is a vertical sectional view on the 70 line 2—2 of Fig. 1, looking in the direction of the arrows.

3 indicates the type bars, pivotally supported at 4 in a known manner, and each actuated through the link 5 leading to the 75 key levers, preferably in the manner disclosed in said Patent No. 1,212,947. 6 is the universal bar to which link 5 is connected by means of the intermediate link 7, the rear 80 end 8 of which is bent to engage the said universal bar 6. Surrounding the intermediate link 7 is a tension spring 9, one end 10 of which is secured to a member 11 carried by the link 5, and the other end 12 of which is bent and passes through a suitable 85 opening in the plate 13. It will, of course, be understood that the invention contemplates the use of a full set of type-bars for the key lever mechanism and that there will be a number of intermediate links 7 and 90 springs 9, equal to the number of type-bars used. Said springs 9, however, will all be connected to the plate 13 as fully described in said Patent No. 1,212,947. The plate 13 is adjustably secured to the upper free end 95 of the frame 14. A convenient means for adjusting the said plate 13 with respect to the frame 14 consists in the set-screws 15 which pass through slots 16 in the plate 13 and into the upper end of the frame 14. It 100 will be understood that by loosening the screws 15 the plate may be raised or lowered, thereby adjusting the position of all the springs 9, after which the screws 15 are brought home and the plate secured in position. The frame 14 is pivotally supported in the casing of the machine. In the form here shown the rear wall 17 of the casing is provided with supporting lugs or ears 18 which serve to receive the trunnions 19 on 110 the frame 14 in a manner well understood. It will be noted that the pivotal point of the

frame 14 is intermediate its upper and lower ends. The lower end 20 of frame 14 is in the form of a bushing for the reception of the adjusting screw or member 21. On the 5 outer end of this member 21 there is a convex head 22 of relatively large size and this convex head is in engagement with a concave surface 23 surrounding an aperture 24 which extends through the rear wall of the 10 casing from the exterior thereof. The said convex head 22 is provided with kerfs 25 of suitable number, while the inner end of the screw 21 is provided with a knurled knob 26 by means of which it may be adjusted. 15 indicates a key or a wrench which may be inserted from the exterior of the rear wall of the casing through the aperture 24 and into engagement with one of the kerfs 25 of the convex head 22. It will be understood 20 that by means of the key or wrench 28 the adjusting member 21 may be turned and when so turned the distance between the lower end 20 of the frame 14 and the rear wall of the casing will be varied, with the 25 result that the upper end of the frame 14 is moved to vary the tension of all the springs 9 simultaneously. The rocking movement of the frame 14 will, of course, carry the member 21 with it and the convex head 22 thereof will slide on the concave surface 23. In 30 order to permit the adjustment to take place throughout a relatively wide range of movement, the convex head 22 is of relatively large size so that it will always engage with the concave surface 23 and will always present a kerf in line with the aperture 24 to 35 permit of adjustment thereof by means of the detachable wrench or key 28.

It will be understood that the convex head 40 22 and the concave face 23 constitute in effect a ball and socket joint and that means for rotatively adjusting the ball extend through the socket.

I claim:

- 45 1. In a typewriting machine, a casing, a frame, controlling the tension of the springs of the type-bars, pivotally supported within the casing and having a member abutting against the rear wall thereof under tension 50 of the springs, and detachable means extending through the rear wall of the casing from the exterior thereof for adjusting the position of the frame with respect to the casing to vary the tension of the springs.
- 55 2. In a typewriting machine, a casing having an aperture in its rear wall, a frame, controlling the tension of the springs of the type-bars, pivotally supported within the casing and having a portion abutting the 60 rear wall of the casing in line with the aperture thereof, and detachable means extending through said aperture from the exterior of said casing for adjusting the position of

the frame with respect to the casing to vary the tension of the springs.

65

3. In a typewriting machine, a casing whose rear wall is provided with an aperture extending through said wall, said aperture terminating on the inside of the rear wall in a concave bearing surface surrounding the aperture, a frame, controlling the tension of the springs of the type-bars, pivotally supported within the casing at a point between its upper and lower ends so that the lower end thereof is normally urged 70 toward the rear wall of the casing under the tension of the springs; an adjustable member in said frame having a convex head in engagement with the concavity of the rear wall, and means extending through 75 said aperture for adjusting said member in the frame to thereby turn the frame on its pivot to vary the tension of the springs.

4. In a typewriting machine, a casing, a frame pivotally supported, within the casing 85 and adjacent to the rear wall thereof, at a point intermediate its upper and lower end, type-bar, springs connected to the upper end of the frame, a rotatably adjustable member carried by the lower end of the frame and 90 abutting against the rear wall of the casing, complementary surfaces on said member and rear wall constituting a ball and socket joint, and means extending through the rear wall of the casing from the exterior 95 thereof and in the plane of the ball and socket joint for rotatably adjusting the member.

5. In a typewriting machine, a casing, a frame pivotally supported, within the casing 100 and adjacent to the rear wall thereof at a point intermediate its upper and lower end, type-bar springs connected to the upper end of the frame, a rotatably adjustable member carried by the lower end of the frame and 105 abutting against the rear wall of the casing, complementary surfaces on said member and rear wall constituting a ball and socket joint, and detachable means extending through the rear wall of the casing from the exterior 110 thereof and in the plane of the ball and socket joint for rotatably adjusting the member.

6. In a typewriting machine a casing, a frame, controlling the tension of the springs 115 of the type bars, pivotally supported within the casing, an adjusting screw or member for the frame, and detachable means extending through the rear of the casing from the exterior thereof for additionally adjusting 120 the position of the frame and thereby varying the tension of the springs.

Signed at New York city, in the county of New York and State of New York, this 8th day of May 1917.

EDWARD B. HESS.

It is hereby certified that in Letters Patent No. 1,241,214, granted September 25, 1917, upon the application of Edward B. Hess, of Brooklyn, New York, for an improvement in "Type-Bar-Adjusting Means," an error appears in the printed specification requiring correction as follows: Page 2, line 88, claim 4, after the compound word "type-bar" strike out the comma; and that the said Letters Patent should be read with this correction therein that the same may conform to the record of the case in the Patent Office.

Signed and sealed this 20th day of November, A. D., 1917.

[SEAL.]

R. F. WHITEHEAD,

Acting Commissioner of Patents.
